HEAD COVERING DEVICE
Elsa C. Guinett and Louis W. Guinett, both of 2600
E. McLoughlin Blvd., Vancouver, Wash.
Filed July 27, 1959, Ser. No. 829,741
1 Claim. (Cl. 132—48)

The present invention relates to a head covering device and more particularly to a head covering device provided with clip means adapted securely to hold the device to the hair of the wearer.

Head covering devices in the nature of bands and the like heretofore proposed have suffered the common fault that they cannot be securely fastened to the hair of the wearer with the consequence that they will not stay in place as desired.

It is a principal object of the present invention to provide a head covering device having clip means at the opposite ends of the bands adapted securely to fasten the device to the hair and hold it in position.

Another object of the invention is to provide a head covering device having new and improved clip means for securing the same to the hair of the wearer.

Other objects and advantages of the invention will become more apparent hereinafter.

In accordance with the illustrated embodiment, the invention comprises a band of flexible material such as a ribbon or the like adapted to extend across the head of the wearer. Secured to the opposite ends of the band are clip means for anchoring the band to the hair of the wearer. The clip means each comprise gripper members which extend transversely with respect to the band for gripping the hair and act securely to hold the band in place.

For a more detailed description of the invention, reference is made to the following specification taken in conjunction with the drawings wherein:

FIG. 1 shows the device of the invention attached to the head of the wearer;

FIG. 2 is a plan view of the device in accordance with the invention;

FIG. 3 is an enlarged view showing details of the clip means in accordance with the invention;

FIG. 4 is a sectional view taken substantially along line 4—4 of FIG. 3;

FIG. 5 is a sectional view of the clip taken substantially along line 5—5 of FIG. 4 showing the clip as it is when attached to the hair; and

FIG. 6 is a view similar to FIG. 5 showing the clip gripper means open for attachment to or removal from the hair.

Referring now to the drawings, the device of the invention comprises a strip or band 10 of flexible material, such as a ribbon or other suitable material, which may be placed on the head of the wearer and which will conform generally to the shape thereof. Secured to the opposite ends of the band 10 are clip means 12. Referring more particularly to FIGS. 3 to 6, the clip means 12 each comprises a body 14 which may be of any decorative configuration on its outer surface 16, but which is provided with a generally flat inner surface 18. Secured to the inner surface 18 are a pair of parallel bars 20, 22, the intermediate portion of each being spaced from the surface 18 by a slight distance so as to enable the band 10 to be inserted therebeneath as may be best seen in FIG. 4. Preferably, the intermediate portion of the bar 22 is of slightly lesser width than the band 10 so as frictionally

2

to engage the band. As best shown in FIG. 4, the band 10 extends beneath the bars 22, 20 and is then looped over the bar 20 and the end portion slipped back beneath the bar 22. This looping action combined with the gripping action of the opposite end portions of the bar 22 upon the opposite edges of the band 10 secures the clip to the band although the position of the clip can be adjusted on the band by suitable manipulation as will be apparent. Means are provided on the clip means 12 for fastening the same to the hair of the wearer. The clip preferably comprises a pair of gripper members 26, 28 which may be formed of a single piece of metal but which are hinged together at one end as indicated at 30. The member 26 is suitably secured as by an adhesive to the outer surface of the bar 22 and is formed at its end opposite the hinge 30 with a hook 32 adapted to engage the end 34 of the other gripper member 28, as shown in FIG. 5, so as to engage strands of the hair of the wearer between the members 26, 28. When the band is fastened in this manner with the gripper members extending transversely with respect to the direction of the band, the band is held securely in place and will not shift in position on the head of the wearer.

Having illustrated and described a preferred embodiment of the present invention, it should be apparent to those skilled in the art that the invention permits of modification in arrangement and detail. I claim as my invention all such modifications as come within the true spirit and scope of the appended claim.

30 I claim:
A head covering device consisting of a single, flexible fabric band adapted to extend across the head of the wearer, a pair of clip means, each of said clip means comprising a body having a decorative outer surface and a substantially flat inner surface, a pair of parallel bars on each of said clip means, means fixing the opposite ends of said bars to said inner surface of the corresponding clip means with the intermediate portion of said bars spaced from said inner surface, said intermediate portion being of lesser width than said band the opposite end of said band being adjustably attached to said clip means, said band ends being threaded respectively beneath both of said bars of one of said clip means and being looped over and threaded back beneath the other of said bars thereon with their edges frictionally engaging said bars, each of said clip means having a pair of hinged connected, elongate gripper members thereon, one of said gripper members of each pair being secured to the outwardly facing surface of said other bar of the corresponding clip means and extending transversely to the longitudinal direction of said band, and cooperating means on each said pair of gripper members for releasably securing the same together so as to clamp strands of hair therebetween.
